UNITED STATES PATENT OFFICE.

CLARENCE E. DRAKE, OF SAN DIEGO, CALIFORNIA.

OIL-BURNER.

1,176,354.

Specification of Letters Patent. Patented Mar. 21, 1916.

Application filed November 28, 1914. Serial No. 874,409.

To all whom it may concern:

Be it known that I, CLARENCE E. DRAKE, a citizen of the United States, and a resident of San Diego, in the county of San 5 Diego and State of California, have invented certain new and useful Improvements in Oil-Burners, of which the following is a specification.

My invention relates to oil burners for 10 use in stoves, ranges and the like and is more particularly adapted for burning distillate, kerosene and the like and the objects of my invention are, first, to provide an oil burner with a part in which the oil is heated 15 in the feed pipe extending to the burner, second, to provide such an oil burner in which said heating part is adjustable so that the flame may be guided in various directions thereby and, third, to provide an oil 20 burner which is simple, durable, easily constructed, easily installed and which does not readily get out of order.

With these and other objects in view as will appear hereinafter my invention consists of certain novel features of construction, combination and arrangement of parts 25 as will be hereinafter described in detail and particularly set forth in the appended claims reference being had to the accompanying drawings and to the characters of reference thereon which form a part of this specification, in which:

Figure 1 is a perspective view of my burner complete, Fig. 2 is a detail top or 30 plan view of the plate which provides means for heating the oil and for directing the flame, Fig. 3 is a detailed fragmentary sectional view of the burner showing the plate and showing by dotted lines the varied position 35 of the plate relative to the burner outlet and the varied positions of the burner outlet to the plate.

Similar characters of reference refer to 40 similar parts throughout the several views. The feed pipe 1, L 2, plate supporting pipe 3, L 4, connecting pipe 5, L 6, fuel outlet pipe 7, generating pan 8, plate 9 and valve 10 constitute the principal parts of my burner.

The plate 9 is provided with an S shaped 45 chamber 9^a therein adapted to increase the circulating area in said plate. This plate 50 is for the purpose of heating the fuel so that it is transformed into a vapor at this point on its way to the outlet 7^b of the burner and it is also for the purpose of

providing a spreader and director for the flame, also for the purpose of providing a heated surface for the vaporized oil mixed with the air to strike against to provide 55 proper combustion. This plate 9 is flat on its normally lower surface and rounding on its normally upper surface and is supported on the pipe 3 by means of pipe threads 9^b and 9^c therein adapted to screw onto the 60 free ends of the pipe 3. This pipe 3 at its one end is connected to the L 2 and this L 2 is also connected to the feed pipe 1 which extends from the oil tank. In this feed pipe 1 is provided the needle valve 10 which is 65 adapted to regulate the flow of oil to the burner. This feed pipe 1 connects with the oil supply tank which is placed a sufficient distance above the burner to afford proper gravity pressure to the burner, however, 70 other means may be used to provide pressure to the burner which is no part of my invention. On the other end of the feed pipe 3 is screwed the L 4 and into this L is also screwed the connecting pipe 5, its other 75 end being screwed into the L 6. Into the other end of the L 6 is screwed the one end of the fuel outlet pipe 7, the other end extending backward normally parallel with the supporting pipe 3 and on its end is provided 80 a cap 7^a. It is provided normally centrally below the plate 9 with a small outlet hole 7^b adapted for the exit of the vaporized fuel from said burner pipe 7 directly 85 beneath this hole is hung a generating pan 8 which is a small pan provided with hooks 90 adapted to hook over the pipe 7 and when it is desired to start the fire when the plate 9 is not hot the valve 10 is turned allowing 95 a small quantity of oil to run into the pan 8 which is ignited with a match and the flame therefrom will heat the plate 9, then the oil may be turned on by means of the needle valve 10 and the fuel is vaporized by 100 means of the heated plate 9 so that when the vaporized fuel reaches said plate a proper gas mixture is provided for proper combustion. It will be here noted that the burner pipe 7 may be turned to various positions radially with the supporting pipe 3 105 by turning the L 4 on said pipe 3 in either direction; that it may be turned in various positions radially to the connecting pipe 5 by turning the L 6 on said pipe 5 or the pipe 5 in the L 4; that the plate 9 can be 110 radially adjusted to various positions, all as shown best in Fig. 3 by the solid and

dotted lines, by simply turning the plate 9 on the ends of the pipe 3 so that the flame may be directed in various directions by means of said plate by shifting it as desired and the pipe 7 may be turned to assist in said regulation.

Though I have shown and described a particular construction, combination and arrangement of parts I do not wish to be limited to this particular construction, combination and arrangement but desire to include in the purview of my invention the construction, combination and arrangement substantially as set forth in the appended claims.

It is obvious that with this construction there is provided an oil burner in which the fuel oil is reduced to a vapor in the feed pipe by the flame; that the plate in which this oil is reduced to a vapor is readily adjustable into various angles for the purpose of spreading and directing the flame of the burner; that the outlet from the burner may be adjusted to various positions relatively to said plate; that the burner is very simple and economical of construction, durable and easily installed.

Having thus described my invention what I claim as new and desire to secure by Letters Patent is:

1. In an oil burner, the combination of an oil conducting pipe consisting of a normally horizontal pipe, a normally vertical pipe connected thereto, another normally horizontal pipe parallel with said first mentioned pipe, all connected by means of L's, a plate screwed onto the end of said last mentioned horizontal pipe provided with an S shaped chamber therein forming a continuation of said oil feed conductor,

another pipe screwed into said plate in alignment with the pipe upon which said plate is screwed, a normally vertical pipe connected thereto by means of an L, another horizontal pipe normally parallel with said last mentioned horizontal pipe provided with an exit hole therein, centrally beneath said plate whereby said plate may be tilted on its supporting pipes relatively to the exit hole in said parallel pipe.

2. In an oil burner, the combination of an oil conducting pipe consisting of a normally horizontal pipe, a normally vertical pipe connected thereto, another normally horizontal pipe parallel with said first mentioned pipe, all connected by means of L's, a plate screwed onto the end of said last mentioned horizontal pipe provided with an S shaped chamber therein forming a continuation of said oil feed conductor, another pipe screwed into said plate in alignment with the pipe upon which said plate is screwed, a normally vertical pipe connected thereto by means of an L, another horizontal pipe normally parallel with said last mentioned horizontal pipe provided with an exit hole therein, centrally beneath said plate whereby said plate may be tilted on its supporting pipes relatively to the exit hole in said parallel pipe and a generating pan suspended on said last mentioned pipe directly beneath the exit hole therein.

In testimony whereof, I have hereunto subscribed my name in the presence of two subscribing witnesses.

CLARENCE E. DRAKE.
